DESIGN FOR A KNIFE

Howard L. Fischer, St. Paul, Minn.

Application May 1, 1947, Serial No. 138,738

Term of patent 14 years

(Cl. D22—3)

To all whom it may concern:

Be it known that I, Howard L. Fischer, a citizen of the United States, residing in St. Paul, county of Ramsey, and State of Minnesota, have invented a new, original, and ornamental Design for a Knife, for which the following is a specification, reference being had to the accompanying drawings, forming part thereof.

I claim:

The ornamental design for a knife, as shown.

HOWARD L. FISCHER.
